ABSTRACT: Disclosed is apparatus for supporting, in horizontal position, an actuating cylinder for a rail-mounted car. The apparatus of the invention includes a stationary support surface beneath the rails on which the car is mounted. A cylinder cradle having two spaced pairs of laterally extending brackets overlying the rails is detachably affixed to the support surface. A pivotally mounted wheel housing containing a wheel rotatable therein is disposed on each of the brackets with the wheel in the housing in engagement with one of the rails. A screwjack is provided threaded through each of the brackets and in pressure contact with the wheel housing attached to each bracket. Pressure may be applied to the wheel housing by turning the screwjack to lift the cylinder cradle from the support surface so that the cradle and the cylinder may be moved along the rails to a point where the cylinder can be conveniently removed from the cradle and a replacement substituted therefor.

SUPPORT APPARATUS FOR THE ACTUATING CYLINDER OF A RAIL-MOUNTED CAR

The present invention relates generally to material handling equipment and, more particularly, to an improved support apparatus for the cylinder of a cylinder-actuated, rail-mounted car.

BACKGROUND OF THE INVENTION

In manufacturing processes such as are involved in the production of continuous steel strip, the steel strip is transported from one station to another in coil form for processing. For such transportation, the coil is carried on a rail-mounted car which is movable along the rails of a submill floor trackway by means of a fluid pressure cylinder which is anchored in horizontal disposition in a concrete cave or compartment. The compartment is located below the mill floor level at the end of the trackway on which the coil car is mounted. The piston rod of the cylinder is connected with the body of the coil car.

Prior to my invention, considerable difficulty and mill operation interruption were encountered whenever it became necessary, due to normal wear or for any other reason, to replace the car-actuating cylinder. Such difficulties arose from the fact that the cylinder was located below the mill floor level in the closely confined area of the cave or compartment. Each time it was desired to replace the cylinder, it was necessary for workmen to descend into the cylinder compartment and begin the replacement operation by unbolting the cylinder from its base. After the cylinder was thus loosened from its base, an intricate and unsafe system of block-and-tackles and come-alongs was used to remove the cylinder from the cave and lower it to the floor of the pit under the coil car trackway from where it could be removed by an overhead crane. This method normally required the services of four workmen for 8 hours which caused a production time loss of 32 man-hours. In addition to being excessively time-consuming, the procedure was unsafe because of the ever-present possibility of sudden or uncontrolled movement of the heavy cylinder as it was being moved caused by the slipping and/or sliding of the cables which were being used to inch the cylinder out of or into its normal anchorage in the cylinder compartment. This procedure was also potentially hazardous for the cylinder itself since sudden slipping and/or sliding of the handling cables could cause the cylinder to be dropped to the pit floor or bumped against the concrete walls of the pit under the trackway which would result in damage to the cylinder.

It is, accordingly, the primary object of my invention to provide an improved support apparatus for the cylinder of a cylinder-actuated rail-mounted car which cylinder is horizontally disposed in a compartment at one end of the trackway along which the car moves, and which apparatus permits ready removal or installation of the cylinder in a safe and damage-free manner.

It is more specialized object of my invention to provide apparatus as set forth in the statement of object above in which the apparatus includes a support surface in the cylinder compartment spaced below the rails of the trackway on which the car is mounted for travel; a cylinder cradle frame detachably supported on the support surface between the rails; two pairs of spaced brackets extending from opposite sides of the cradle and overlying the rails of the trackway; a wheel housing, having a wheel rotatably mounted therein, pivotally mounted on each of the brackets with the wheel in engagement with one of the rails of the trackway; a screwjack on each of the brackets in adjustable engagement with the wheel housing mounted thereon whereby the cradle is adapted to be pivoted relative to the wheel housings and be raised clear of the support surface thereby permitting the cradle and the cylinder supported thereby to be moved out of the compartment along the rails of the trackway.

BRIEF DESCRIPTION OF THE DRAWING

FIG. 1 is a plan view;

FIG. 2 is a side elevational view of FIG. 1 partly in section; FIG. 3 is a cross sectional view taken along the line III-III of FIG. 2 with a cylinder housing shown by broken lines; and FIG. 4 is an enlarged partial elevational view of the wheel housing arrangement of the invention.

DESCRIPTION OF THE PREFERRED EMBODIMENT

Referring more particularly to the drawing, reference numeral 2 designates the trackway, which includes a pair of spaced parallel rails 4, upon which a coil car 6 is wheel mounted for travel therealong. The coil car 6 is provided with a coil nest 8 projecting upwardly from its base for carrying a coil of strip steel between processing stations (not shown) adjacent and above the trackway 2.

The coil car 6 is actuated along the trackway by means of a fluid pressure cylinder 10 having a piston rod 12 reciprocal therein connected with the base of the car 6. The cylinder 10 is disposed in horizontal position within a cave or compartment 14 below the floor level F of the mill.

The structure thus far described is conventional except for the support apparatus of the invention which will now be described in detail.

The support apparatus of the invention, designated generally by reference numeral 16, is normally disposed in the compartment 14 and consists of a plurality of transversely extending T-shaped beams 18 under the portion of the trackway 2 which extends into the compartment 14. The beams 18 extend between longitudinally extending H-beams 20 upon which the rails 4 of the trackway 2 are supported. Each of the T-beams 18 is provided with a flange 22 on its underside adjacent each end thereof which flanges rest on the bottom flanges of the H-beams 20, as best shown in FIG. 3.

A bedplate 24 is detachably affixed to the upper flange surface of each of the T-beams 18 by nut-and-bolt means 26 which project through diametrically opposite corners of the plates and through the upper flanges of the T-beams 18. A cradle frame 28 which is substantially H-shaped in configuration having upright sides 30 and a cross plate member 32 extending between and connecting the sides 30 extends along the support surface formed by the T-beams 18, resting on the plates 24. The bottom of the side members 30 of the cradle frame 28 are rigidly affixed to the bedplates, as by welding.

A housing 34 is removably attached to opposite ends of the cradle frame 28 by nut-and-bolt means 36, which pass through the lower portions of the housings 34 and the cross plate 32 of the cradle frame. The cylinder 10 is detachably confined by the housings 34 in conventional manner.

The upright sides 30 of the cradle frame 28 are vertically extended adjacent each end of the frame, as at 37, to a height above the level of the rails 4 and have projecting normal therefrom brackets 38 which overlie the rails 4 on opposite sides of the ends of the cradle frame 28. Pairs of spaced, parallel gusset plates 40 may be provided affixed to and extending between the outer surfaces of the sides 30 and the undersurfaces of the brackets 38 to aid in supporting the brackets. Pairs of spaced reinforcing plates 41 extend between the bottom portions of the cradle sidewalls 30 aligned with gusset plates 40.

Stop members 46 in the form of blocks may be welded or otherwise rigidly affixed adjacent the forward edge of the upper flange of each of the T-beams 18 for the purpose of limiting movement of the bedplates 24 in the direction of the piston end of the cylinder 10. Although the nut-and-bolt means 26 are sufficient to hold the bedplates 24 in position during normal operations, the stop blocks 46 insure against shearing of the nut-and-bolt means 26 under excessive or abnormal strain.

Upright reinforcement plates 42 may be affixed, as by welding, to the bedplates 24 extending upwardly and welded to the outer vertical surfaces of the sides 30 of the cradle frame 28 for further rigidifying the frame structure.

A short supporting lug 44 is affixed to the underside of each of the brackets 38 adjacent the end thereof for pivotally

mounting the apex end 50 of a substantially triangular-shaped wheel housing frame 52. The wheel housing frame 52 is pivotally mounted on the lug 44 by means of a shaft 54 which extends through the wheel housing frame and the tubing 44. A wheel 56 is rotatably carried by the wheel frame 52 in the end thereof remote from its apex end 50 for engagement with and travel along one of the rails 4. The upper portion of each wheel frame 52 above the wheel 56 is formed with a bearing plate 58 which cooperates with a jackscrew 60. Jackscrew 60 is threaded through an internally threaded boss 62 on the top surface of each bracket and an internally threaded opening 64 provided through the bracket aligned with the boss 62.

In operation, whenever it becomes necessary to remove cylinder 10 for replacement or maintenance purposes, the cylinder is actuated to project its piston rod 12 to move the coil car 6 to a point remote from the compartment 14 along the trackway 2. The coil car is securely tied into position at this remote point by cables or other means (not shown). A workman then enters the compartment 14 and disconnects the cradle frame 28 and bed plates 24 from the T-beams 18 by removing the nut-and-bolt means 26. After the cradle frame assembly has been loosened, the workman then proceeds to turn the jackscrews 60 to cause the wheel housings 52 to rotate about the pins 54. This causes the cradle frame 28 and the bedplates 24 to rise above and clear the upper flanges of the T-beams 18 and the stop blocks 46. Cylinder 10 is then actuated to cause retraction of the piston rod 12. Since the piston rod is securely fastened to the coil car 6 and the coil car is anchored at a point remote from the cylinder 10, actuation of the cylinder 10 to retract the piston rod will cause the cylinder and the cradle 28 together with bedplates 24 to move along the rails 4 on the wheels 56 out of the compartment 14. After the cylinder and cradle assembly has thus been moved out of the compartment 14, the cylinder 10 can easily be disconnected from the cradle frame 28 by removal of the nut-and-bolt means 36. The piston rod 12 is then disconnected from the coil car and the cylinder is removed from the cradle frame 28 by means of an overhead crane.

After the cylinder has been removed from the cradle frame as explained above, a new or reconditioned cylinder is lowered by crane to the empty cradle frame 28 and attached thereto by reinstalling the nut-and-bolt means 36, after which the piston rod 12 may be connected to the coil car 6, which is still securely tied at a point along the trackway 2 remote from the compartment 14. The cylinder 10 is then actuated to project the piston rod 12 which action causes the cradle frame 28 bed assembly 24 to roll along the rails 4 into the compartment 14. When the cradle frame bedplate unit has been properly positioned above the T-beams 18, jackscrews 60 are turned sufficiently to allow the cradle frame 28 and the bedplates 24 to drop into contact with the T-beams 18 after which the bedplates 24 are again affixed to the T-beam 18 by means of nut-and-bolts 26. The coil car 6 is then released from anchorage so that it is free to move along the trackway 2 in a normal manner.

Thus, it will be seen that the objects set forth above to which

the invention has addressed itself have been accomplished. Through use of the apparatus of the invention, the replacing of the cylinder 10 can be accomplished by two men in about 1 hour for a total of two man-hours as compared to the need for four men in 8 hours for a total of 32 man-hours required prior to my invention. The apparatus of the invention further makes it possible to use a safer method for removing a coil car cylinder and a method in which there is a minimum danger of damage to the cylinder while it is being removed or installed.

It will be noted that, if desired, the loosened cradle frame 28 and bedplates 24 may be manually withdrawn from the compartment 14. When this is done, the piston rod 12 is disconnected from the coil car 6 and remains in retracted position in the cylinder 10. The coil car 6 remains at a point remote from the compartment 14 but is not secured there. In this method after the cradle frame and bedplate assembly has been loosened and raised clear of the T-beams 18, the cradle frame 28 may be grasped and manually pulled along the rails 4 out of the compartment 14.

I claim:

1. In a rail-mounted car movable along a pair of rails by the piston rod of an anchored fluid pressure cylinder horizontally disposed in a compartment at one end of said rails, said rails extending into said compartment, the improvement therewith of support apparatus for said cylinder in said compartment, said apparatus comprising a rigid support surface in said compartment spaced below said rails, a cradle frame supported on and extending along said support surface between said rails, means detachably affixing said cylinder to said cradle in horizontal position, a pair of spaced brackets extending from opposite sides of said cradle and overlying said rails, a wheel housing having a wheel rotatably mounted therein pivotally mounted on each of said brackets with said wheel in engagement with one of said rails, jack means on each of said brackets in adjustable engagement with the wheel housing mounted thereon whereby said cradle is adapted to be pivoted relative to said wheel housings and be raised clear of said support surface thereby permitting said cradle and cylinder to be moved out of said compartment along said rails, and means detachably affixing said cradle to said support surface when said cradle is resting on said support surface.

2. Apparatus as defined by claim 1 in which said means detachably affixing said cradle frame to said support surface includes a plurality of transversely extending bedplates spaced along said support surface, said bedplates being rigidly affixed to the bottom of and extending beyond the sides of said cradle frame, and detachable bolt means securing said bedplates to said support surface, said detachable bolt means projecting through said support surface and the portions of said plates extending beyond the sides of said cradle frame.

3. Apparatus as defined by claim 2 including rigid stop plates on said support surface adapted to be engaged by the bedplates when said cradle frame and bedplates are resting on said support surface whereby movement of said bedplates along said support surface is limited.
